UNITED STATES PATENT OFFICE.

OLIVER M. EDWARDS, OF SYRACUSE, NEW YORK.

SASH-HOLDING DEVICE FOR WINDOWS.

1,191,163.

Specification of Letters Patent. Patented July 11, 1916.

Application filed October 27, 1910. Serial No. 589,313.

To all whom it may concern:

Be it known that I, OLIVER M. EDWARDS, a citizen of the United States, residing in the city of Syracuse, county of Onondaga, 5 and State of New York, have invented certain new Improvements in Sash-Holding Devices for Windows, of which the following is a full, clear, and exact description, reference being had to the drawing accompanying and forming a part of the same.

The invention relates to "sash holders" or sash holding devices and their application to windows for holding the sashes therein.

The object of my invention is to provide 15 a simple, cheap and improved "sash holder" or holding device adapted to be used on either the right or left hand stiles of the sash singly to lock or hold the sash against rattling and opening or closing movement, and the invention consists in the combination 20 of the parts or devices hereinafter set forth and particularly pointed out in the claims hereunto annexed and forming a part of this specification.

Like letters of reference, wherever they occur, indicate corresponding parts in the several figures of the drawing.

Figure 1 illustrates one embodiment of my invention applied to a window, the 30 greater portions of the sash and frame of the window being omitted; Fig. 2 illustrates that which is shown in Fig. 1 on line 2-2 thereof, when looking to the right, portions of the sash holder being seen partly in section and partly in full lines; Fig. 3 illustrates the sash holder or holding device seen in Figs. 1 and 2 on an enlarged scale with portions of the casing thereof removed to better illustrate the construction of the movable parts of the holder. Fig. 4 is a transverse sectional view taken on the plane of a horizontal line extending through the sash holder in Fig. 2 and showing particularly the bevel of the recesses and also of the 45 holding members.

A represents the frame of the window, B the sash movable in the guideway of the frame C and the glass.

D represents the "sash holder" which is 50 provided with two movable holding members or parts, d, d', and a casing E, which is adapted to be mounted on the window sash as sash holding devices are many times mounted. The casing E is provided with a 55 cover or part e which is removable from the main portion of the casing and which,

when in place holds the movable portions of the sash holder in proper working relation to one another and the casing. The movable holding members d d', are pivotally mounted in the casing E, as shown, and they are preferably provided with rounded beveled surfaces h h', respectively, and also with finger or thumb pieces i i', respectively, by which such movable holding members are moved out of holding position when the sash is to be moved in the guideway for opening or closing the window. These holding members d d' are eccentrically pivoted in the casing so that when they are operated by 70 grasping the finger pieces i i', such finger pieces are moved toward each other, the beveled rounded portions h h', being thereby moved out of their holding positions relatively to the window frame or to a series of 75 projections k' and recesses k formed upon a strip K, preferably mounted on the window frame, the projections and recesses being preferably so proportioned that the holding members, as d d', when in the holding position, will be received by adjacent recesses with a projection intermediate of the holding members. These recesses and projections are preferably so formed that one of the holding members will be received by 80 one recess and the other member by another recess, the intermediate projection and those adjacent and next to the members d d', forming abutments against which such movable members, as d d', abut and hold the sash against movement in the opening and closing directions, one member, as d, holding the sash in one direction and the other member, as d', holding the sash against movement in the other direction. This will 85 be the case whether such holding members of the sash holder be provided with the rounded beveled surfaces or not. When such eccentrically pivoted members d d', are provided with the rounded beveled surfaces, as h h', and the notches and recesses are employed, they will preferably be so formed as to properly coact with the beveled rounded surfaces and thereby hold that portion of the sash to which the holding devices 90 is secured against movement in a direction crosswise of the opening and closing movement of the window or, in other words, hold that portion of the sash to which the holder is attached against rattling and to exclude 95 dirt, dust and drafts of air from passing between that portion of the frame against

which the sash is forced by the action of the beveled rounded surface, as above explained. These holding members d d' , of the sash holder are movable independently of each other out of their holding positions by the hand of the operator and are moved into such holding positions by springs J , preferably formed from a single piece of material so shaped as to have two similar portions j j' , respectively, to engage with the holding members, d d' , as shown, or otherwise as desired. As shown such portions have two points of engagement by which each holding member is moved by the tension of such portions of the spring or springs in directions to lock or hold the sash in the frame. These portions, as j j' , of the spring or springs are so arranged relatively to the holding members h h' that the finger pieces thereof are moved away from one another as such holding members are moved into the holding positions. These portions j j' , when formed as shown, are preferably made to engage with the holding members h h' axially of the pivots on which such members turn and also adjacent to the finger pieces i i' , respectively. As here shown, each of these holding members, as d d' , is provided with a hub portion and one portion of the spring or springs J is received by each of such hub portions being coiled around the same axially of the pivots on which the holding members are mounted. These holding members d d' , are herein shown as abutting against the end portions of the casing E adjacent to the finger pieces i i' , thereof, so as to limit the movement of such finger pieces in the holding direction of movement.

When the holder D is in the position seen in Fig. 1, the movable member d thereof is in engagement with the frame of the window and any force applied to move the sash upwardly is resisted by such holding member mounted upon its pivot and, if moved sufficiently, abutting against the upper end portion of the casing E . To free such sash holder from the holding action of the member d such member must be moved out of engagement with the frame of the window, which is done by moving the finger piece i toward the finger piece i' at the opposite end portion of the holder. In like manner the member d' , is in engagement with the frame of the window and resists the movement of the sash in a downward direction until such member d' is moved out of holding position by moving the finger piece i' toward the finger piece i at the upper end of such holder. Of course, if projections and recesses are employed on the frame, as shown in Figs. 1 and 2, the movement of such holding members, as d d' , must be sufficient for their holding surfaces to pass clear of the projection, as k , when the sash is to be moved for opening or closing the window. If such projections and recesses be not employed, then the movement of such members will be only sufficient to free the sash from the frictional holding action of the rounded beveled surfaces upon the coacting surface of the window frame, as is the case in many constructions of window fixtures now in quite extensive use. By reason of there being two holding members, as d d' , for each holding device or holder and such members moving in the directions herein shown, the holders are reversible and can be used on either the right hand stile of the sash, as shown in Figs. 1 and 2, or upon the left hand stile as desired, the action being identically the same in either case, there being one holding member to resist the upward movement of the sash and also one member to resist the downward movement of the sash.

What I claim as new is:

The combination with a window frame provided with a plurality of cut-outs having beveled faces, of a sash holder comprising a pair of spring pressed levers pivoted to the sash contiguous to each other on parallel axes and having eccentrically arranged peripheral and beveled cam faces complementary to the beveled faces of the cut-outs and curving about the axes of the levers, the levers being arranged to operate in opposite direction, substantially as and for the purpose specified.

OLIVER M. EDWARDS.
